(57) **CLAIM**

The ornamental design for a clear pump adapter, as shown and described.

DESCRIPTION

FIG. 1 is a front view of a clear pump adapter showing my new design;

FIG. 2 is a backside view;

FIG. 3 is a right side view;

FIG. 4 is a left side view;

FIG. 5 is a top plan view;

FIG. 6 is a bottom plan view;

FIG. 7 is a bottom left side perspective view; and,

FIG. 8 is a top left side perspective view.

In the drawings, the pump and the analyzer are shown in broken lines for illustrative purposes only and form no part of the claimed design.
